UNITED STATES PATENT OFFICE.

WILLIAM E. WHITE, OF CHICAGO, ILLINOIS, ASSIGNOR TO KALMAN STEEL COMPANY, OF CHICAGO, ILLINOIS, A CORPORATION OF DELAWARE.

ROAD-STRIP AND DOWEL-BAR SUPPORT.

Application filed October 11, 1926. Serial No. 140,883.

My invention relates to concrete road construction and particularly to a novel temporary support for the strip and transverse dowel bar.

5 In the building of roads, it is common practice to provide a longitudinal strip located at the center of the road acting as a parting strip, the strip being of generally channel shape in cross section, thereby providing a 10 tongue and groove in the abutting slabs of concrete. It is the custom also to provide short lengths of rods or bars extending transversely across the parting line and located at suitably spaced intervals for the 15 purpose of tying together the adjacent slabs.

Obviously means must be provided for positioning the strip and bar sections prior to and during the pouring of the concrete, and many expedients have been adopted for that 20 purpose. The device here disclosed is intended as a temporary support both for the strip and bar, the device being lifted vertically from the plastic mass after it has accomplished its purpose; thus the devices are 25 salvaged and repeatedly used.

A feature of importance in the device here disclosed is that its stability is dependent not on penetration of the supporting soil, but on the lateral bracing effect of the side 30 arms or legs. This will be found to be of advantage where the soil is hard or rocky; in any event, it avoids the necessity for extensive driving of stakes and reduces the amount of force necessary to remove the 35 holder after the concrete is poured. When the device herein disclosed is used, the vertical holes commonly provided in the channel of the strip are unnecessary. The elimination of the punching cost and the cost of the 40 stakes heretofore used serves to materially reduce the cost of the work.

The invention will be more readily understood by reference to the accompanying drawing, in which:

45 Fig. 1 is a side elevation of the device constructed in accordance with my invention; and

Fig. 2 is an edge view thereof.

In the drawings, the road strip is indicated 50 at A and the dowel bars at B, only one of

which is shown. The road strip is of common construction, having a V-shaped channel, 10, at a point midway of its height. An aperture is provided at the angle of the V-shaped channel for the accommodation of 55 the dowel bar B.

The supporting device comprises a pair of channel-shaped members, of duplicate form, each having a vertical leg, 11, 12, an inclined leg, 13, 14 and a connecting member, 15, 16. The terminal portions of the respective legs are pointed in order to easily penetrate the soil to the limited extent indicated. It will be noted that the stability of the device is not dependent upon penetration but upon the lateral bracing effect of the structure. The pair of members are united by means of the head, 17, the sides of which are riveted to the flanges of the channel. An opening, 18 may be provided in the head for 70 engagement in lifting the device from the concrete. A notch, 19, is provided in the side members of the head at a point directly above the space occupied by the road strip A. Thus it will be seen that the strip is held down 75 wholly by engagement of the device with the dowel bar.

Each of the four legs, 11, 12, 13, 14, is provided with a notch, 20, at the bottom, by means of which the legs straddle the bar B. 80 Thus the bar is held down on two sides of the strip and is firmly positioned.

With the parts in the position shown in the drawings, the rough concrete is poured approximately to the height indicated by the 85 broken line in Fig. 1, which will leave the head, 17, and the connecting members, 15, 16 projecting thereabove. The supporting device is then lifted vertically leaving the strip and bar in place in the concrete, after 90 which the surfacing is done.

The device is of extreme simplicity, strong and rigid in construction and adapted for use for an indefinite period.

Changes in the form and arrangement of 95 the parts may be made without departure from the spirit of my invention.

I claim:

1. In a device for co-operation with a strip and dowel bar, the combination of a pair of 100

vertical members adapted to engage two sides of the strip, to hold it in a vertical position, and a pair of lateral brace members adapted to engage the top side of the bar, at opposite sides of and laterally removed from the vertical members, and means uniting said vertical and brace members.

2. In a device for co-operation with a strip and dowel bar, the combination of a pair of vertical members adapted to engage two sides only of the strip, to hold it in a vertical position, and a pair of lateral brace members adapted to engage the top side of the bar, at opposite sides of and laterally removed from the vertical members, and means uniting said vertical and brace members.

3. In a device for co-operation with a strip and dowel bar, the combination of a pair of vertical members lying alongside of the strip and adapted for slight penetration of the soil, and a pair of brace members having bifurcated extremities adapted to receive the bar at a point laterally removed from the vertical members, and means uniting the vertical and brace members.

4. In a device for co-operation with a road strip and dowel bar, the combination of a temporary holder for said strip and bar, said holder consisting of four laterally separated legs, the two intermediate legs engaging the sides of the strip for the purpose of holding it in a vertical position, and the two outside legs bracing the structure against lateral deflection.

5. In a device for co-operation with a strip and dowel bar, the combination of a holder comprising four legs and a head for joining the legs, two of the intermediate legs being positioned to engage opposite sides of the strip whereby to maintain it in a vertical position, and the two outside legs engaging the bar at points a substantial distance laterally from the strip and functioning to brace the structure during the pouring of the concrete.

6. A temporary holding device for a strip and bar, comprising a pair of inverted U-shaped members, a head for joining said pair of members whereby a rigid four-legged structure is formed, the space between the two intermediate legs being proportioned to receive a strip and the two outside legs being provided with means for engagement with the bar and acting to brace the structure without substantial penetration of the soil.

7. In a device of the class described, the combination with a strip, of a pair of vertical members adapted to engage the sides of the strip, to hold it in a vertical position, a pair of lateral brace members positioned to engage the top surface of the soil and hold the structure against side tipping and a head joining all of said members and adapted to project above the level of the concrete poured around said strip.

8. A holding device for road strips com-

prising a pair of channels bent into inverted U-shape a head for joining the bar, the space between the intermediate two legs being proportioned to receive and tightly hold the strip therebetween, the outside two legs acting as braces to maintain a stable structure without material penetration of the soil by the legs.

In testimony whereof I have affixed my signature.

WILLIAM E. WHITE.
